UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

BUILDING.

Application filed March 9, 1925. Serial No. 14,105.

This invention relates to buildings and more particularly to storage buildings such as garages of the type wherein the several floors are connected by ramps over which vehicles may be driven from floor to floor, and one of the objects of the invention is to improve and simplify the structure of such buildings.

In the drawing:

- 10 Fig. 1 is a horizontal sectional view of the building taken on the line 1—1 of Fig. 2;
- 15 Fig. 2 a vertical section taken on the line 2—2 of Fig. 1;
- 20 Fig. 3 a vertical section taken on the line 3—3 of Fig. 1;
- 25 Fig. 4 a vertical section taken on the line 4—4 of Fig. 1; and
- 30 Fig. 5 a vertical section taken on the line 5—5 of Fig. 1.

Referring in detail to the structure shown in the drawing, the outer walls 1 of the building enclose a series of superposed storage floors 2. As shown, the building is designed for use as a garage and each floor is divided into individual storage spaces by partitions or curbings 3.

The several floors of the building are connected by ramp structures over which motor vehicles may be driven from one floor to another to and from their storage spaces. These ramp structures are located at substantially the center of the building and each structure comprises a main ramp 4 of considerable length suspended between each pair of floors, and terminating short of said floors. Connected to the lower end of the ramp 4 is a lower landing or platform 5. This platform is elevated above the lower of the pair of floors, and the landing and the lower end of the ramp 4 are supported by the said lower floor. Leading from the lower floor to the lower landing 5 is a relatively short ramp 6 which extends transversely to the direction of the main ramp 4. The upper end of the ramp 4 leads to a horizontal upper landing 7. This landing is suspended below the upper floor and is of considerable length, extending transversely from the ramp 4 to one of the side walls of the building. A short ramp 8 connects one end of the landing 7 adjacent the ramp 4 with the upper floor. This ramp 8 extends transversely to the direction of the main

ramp and longitudinally from the end of the landing 7. The landings 5 and 7 may be horizontal throughout their entire area, as shown, or they may be suitably inclined or warped to properly meet and coincide with the ramps to which they are connected.

The outer end of the landing 7 adjacent the side wall of the building is provided with a pair of storage spaces to receive motor vehicles and located inwardly of said storage spaces, between said spaces and the main ramp connection are a pair of short oppositely extending ramps 9. These ramps extend transversely from the opposite longitudinal sides of the landing and connect the landing with the floor just above it. The landing 7, the ramps 8 and 9 and the upper end of the main ramp 4 are all suspended from and supported by the upper floor. The floor is cut away over the ramps and the landings to provide clearance for the ascending vehicles. Extending along the edges of the ramps and the landings and also around the edges of the openings are suitable guard rails or curbings 10.

The ascent and descent structure described is duplicated between all of the storage floors of the building and said structures are preferably superposed in vertical alignment and parallel to each other. An entrance 11 leads to the ground floor of the building and each floor is laid out to provide a corridor connecting the ramps 6 and 8 which communicate with that floor, and this corridor also leads from the said ramps to the vehicle storage spaces upon that side of the building. It will be seen therefore that vehicles may be driven over the ramps 6, 4 and 8 and over said corridor spaces, on a substantially spiral path, from the ground floor to upper floors of the building. Each floor is also laid out to provide a corridor extending in a line with the short ramps 9. This corridor connects the ramps 9 with the storage spaces of the floor upon this side of the building. Both corridors extend throughout the length of the building and the vehicle storage spaces are arranged along their opposite sides. The storage space of each floor is divided into two sections by division lines 12 which extend from the ends of the ascent structures to the end walls of the building. The division lines 12 may be defined by curbing or by partition walls.

The ramps 8 and 9 and the landing 7 provide a vehicle passage-way connecting the two floor sections. The particular arrangement of the ramps 6 and the platform 7 with relation to the corridors avoids the necessity of providing a transverse corridor connecting the two longitudinal corridors. The space along the division lines 12, between the ascent structures and the end walls of the building, is therefore all available for storage purposes. This arrangement also makes it possible for vehicles ascending the main ramp to be driven over the landing 7 and over the ramps 15 8 and 9 directly into either of the two corridors and directly to their assigned storage spaces.

It will be seen from the foregoing description and from the drawings that the ramps and landings are so designed and arranged with relation to the floors as to provide for the ascent of the vehicles by easy stages and also to conserve storage space upon the floors. The extended upper landings 7 and the arrangement of the ramps 9 effects a saving in storage space upon each floor. The outer ends of the landings 7 are available for storage purposes and the ramps 9 are arranged in the corridors and therefore do not take up storage space.

What I claim is:

1. A building comprising outer walls, a series of superposed floors, a series of elongated superposed landings of material length each located between a pair of floors, a series of upper ramps each extending longitudinally from an end of one of said landings to the floor above it, a series of superposed main ramps each extending downwardly from one of said landings transversely from the end thereof to which the upper ramp is connected, said main ramp terminating short of the lower floor, a series of lower ramps each connected to the lower end of the main ramp and extending transversely therefrom in the same direction in plan as the upper ramp, each of said landings being substantially the width of the main ramp connected to it and formed to provide a storage space located in a position spaced away from the main ramp connection longitudinally of the landing and each floor being laid out to provide a pair of corridor spaces extending at opposite sides of the main ramps parallel thereto and communicating with storage spaces along their length, one of said corridors connecting the upper and lower ramps leading to the floor and the other corridor extending transversely into the landing between the main ramp and the storage space on the landing, and a relatively short ramp in said second corridor leading from one side of the landing to the floor above it.
2. A garage building comprising outer walls, a series of superposed storage floors each laid out to provide a pair of parallel corridors spaced outwardly from opposite sides of a longitudinal central vertical plane through the building and storage spaces along both sides of each corridor, a series of superposed main ramps located along one side of said central plane intermediate the length of the building, each ramp being located between a pair of said floors and terminating short of them at its upper and lower ends, a series of elongated superposed upper landings each depressed below one of said floors and connected to the upper end of one of said ramps and being substantially the width of said connected ramp, the said landings each extending transversely from said central plane and across one of the corridors to one of the outer walls and providing a storage space thereon at said wall, two series of superposed short ramps extending transversely of the main ramps oppositely to the direction of the landings, one series connecting the landings with the floors immediately above them and the other series leading from the lower ends of the main ramps to the floors immediately below them, the ramps of both series leading transversely from the opposite longitudinal edges of each landing directly into the corridor crossed by said landing.
3. A garage building comprising outer walls, a series of superposed storage floors each laid out to provide a pair of parallel corridors spaced outwardly from opposite sides of a longitudinal central vertical plane through the building and storage spaces along both sides of each corridor, a series of superposed main ramps located along one side of said central plane intermediate the length of the building, each ramp being located between a pair of said floors and terminating short of them at its upper and lower ends, a series of elongated superposed upper landings each depressed below one of said floors and connected to the upper end of one of said ramps and being substantially the width of said connected ramp, the said landings each extending transversely from said central plane and across one of the corridors to one of the outer walls and providing a storage space thereon at said wall, two series of superposed short ramps extending transversely of the main ramps oppositely to the direction of the landings, one series connecting the landings with the floors immediately above them and the other series leading from the lower ends of the main ramps to the floors immediately below them, the ramps of both series leading into the corridors upon the side of the central plane opposite to the location of the landings, and short ramps leading transversely from the opposite longitudinal edges of each landing directly into the corridor crossed by said landing.

tion of the landings, and short ramps lead- of the ramps into said spaces, whereby the
ing transversely from the opposite longitudi- row of storage spaces along said wall will be
dinal edges of each landing directly into the unbroken. 10
corridor crossed by said landing, said short In testimony whereof I, hereunto affix
ramps being laterally connected with stor- my signature.
